UNITED STATES PATENT OFFICE.

ELWOOD J. RODGERS, OF OMAHA, NEBRASKA.

SOUND-REPRODUCER.

1,259,466.

Specification of Letters Patent. Patented Nov. 16, 1920.

Application filed March 21, 1919. Serial No. 284,226.

To all whom it may concern:

Be it known that I, ELWOOD J. RODGERS, a citizen of the United States, and a resident of Omaha, in the county of Douglas and 5 State of Nebraska, have invented certain new and useful Improvements in Sound-Reproducers, of which the following is a specification.

My invention relates to sound reproducing mechanism, and especially to reproducers adapted for use with disk sound records having various types of record-grooves therein. There are now extensively sold in this country three distinct types of 15 disk sound records, of which the characteristics may be briefly stated as follows: (a) Records in which the spiral groove is V-shaped in vertical section, and in which the undulations are lateral or in the plane of the 20 disk. (b) Records in which the groove is U-shaped or rounded at the bottom and the undulations vertical or of the so-called hill-and-dale form. (c) Records having vertical or hill-and-dale undulations, but in which 25 the groove is essentially V-shaped in vertical section. To obtain satisfactory reproduction from records of these various types, it is essential that the reproducer stylus should rest upon and traverse the record in as 30 nearly as possible the same way as the recording stylus employed by the makers for cutting the original or master records. It is also necessary that the pressure of the stylus upon the record be suited to the type 35 of record, and that the form of and materials used in the styli be suited to the respective records, if the most satisfactory reproduction is to be obtained. It is also desirable that the reproducing stylus should engage the record at the proper angle to the 40 surface thereof, and that the stylus should be in a vertical plane substantially tangent to the record-groove at the point of contact of the stylus therewith, especially when the 45 stylus-position is inclined to the surface of the record. With the foregoing in view, it is the object of my invention to provide a sound reproducer capable of use with records of any of the various types mentioned, and 50 constructed so that it may be adjusted by a single simple operation to properly meet any of the various combinations of requirements above mentioned, according to the type of records to be reproduced; or, in 55 other words, to provide a universal repro-

ducer with which, in changing from one type of record to another, a single simple adjusting operation serves to change all of the necessary structural factors for obtaining the most perfect results with each kind 60 of record. A further object of my invention is to provide a metallic stylus-lever, pivoted in a plane offset from the plane of the diaphragm, but which may be directly connected with the diaphragm without having 65 a tendency to distort the same unsymmetrically and thus reduce the clarity of reproduction or the volume of sound. More particular objects of my invention will be hereinafter set forth in detail. 70

In the accompanying drawings Figure 1 is a side view of mechanism embodying my invention, the reproducer being adjusted for use with the first above mentioned (a) type of records, Fig. 2 is a horizontal section of the mechanism, mainly in the plane of the line 2—2 of Fig. 1, Figs. 3 and 4 are vertical sectional views taken respectively in the planes 3—3 and 4—4 of Fig. 2, Fig. 5 is a partial side view, with the reproducer shown in vertical section and in position for use with records of the second above mentioned (b) type, Fig. 6 is a bottom face view of the reproducer showing the diaphragm which is in operative position in Fig. 5, Fig. 80 7 is a similar view showing the diaphragm used with the third above mentioned (c) type of records, Fig. 8 is a view similar to Fig. 5 but having in operative position the diaphragm and stylus-lever shown in Fig. 7, Fig. 85 9 is a similar view showing the diaphragm used with the third above mentioned (c) type of records, Fig. 8 is a view similar to Fig. 5 but having in operative position the diaphragm and stylus-lever shown in Fig. 7, Fig. 90 10 and Figs. 9 and 10 are diagrammatic views of stylus-levers and diaphragms, illustrating the tendency of a rigid stylus-lever to distort the diaphragm unsymmetrically, and the way in which my improved stylus-lever 95 avoids such unsymmetrical distortion.

The reproducer mechanism provided by my invention is intended for use in connection with any suitable machine for rotating a sound-record disk at a controlled uniform 100 speed, and having suitable sound-projecting or amplifying means, such machines being well known and usually having a horizontal rotary table A on which the record-disk is laid and centered, and over which the reproducer is traversed, the latter being carried by a horizontally swinging tone-arm which connects the sound-box with the horn or amplifying sound-conduit. In the structure shown I employ a tubular tone-arm 11 of 110

the usual tapering form, the larger end thereof being turned downwardly and being pivotally connected with a fixed base 12 by any suitable means such that the horizontal portion of the arm may swing above the rotary table A, parallel therewith, and to an extent such as to pass over the grooved portion of a record-disk upon the table. Near the outer or front end of the tone-arm 11, the same is turned laterally to form a hollow bearing-member 13 for a tubular arm 14 which is mounted thereon so as to be swingable in a vertical plane about said bearing-member. A circular port 15 in the front side of the bearing-member connects the passage through the tone-arm with that through the arm 14. As shown in Fig. 2, said arm is held upon the bearing by a washer 16 and screw 17 which passes through the washer into the closed end of the hollow bearing-member. Opposite the port 15 there is a slot 18 extending partially around the wall of the member 13, and a rod or small shaft 19, carried by the arm, extends through said slot to limit the swinging movement of the arm about the bearing-member. Said rod 19 has an additional function hereinafter set forth.

A thin collar 20 is formed integrally with the tubular arm 14 near its bearing on the member 13, and the sound-box sleeve 21 fits revolvably around said collar and the portion of the arm which extends beyond the collar. At its outer or front end said sleeve is closed by a removable plate 22, and adjacent to said plate there is a transverse wall 23 integral with the sleeve and having an axial opening into which is fitted a portion of the rod or shaft 19, said portion of the shaft being squared, threaded terminally, and provided with a nut 24, so as to be fixedly connected with the sleeve. Diaphragm-casings 30, 40 and 50 are formed integrally with the sleeve 21 and arranged in an equilateral triangular form about the axis thereof as best shown in Fig. 3. Said casings are chambered cylindrically to receive respectively the diaphragms 31, 41 and 51, the edges of the diaphragms being held between pairs of resilient tubular rings 32, 42 and 52 disposed peripherally of the chambers and retained therein by metal rings 33, 43 and 53 which are removably secured to the faces of the casings by suitable screws. At the inner sides of the diaphragm-chambers there are openings or passages 34, 44 and 54, each of which is circular in the plane at which it opens to the chamber, but is elongated axially of the sleeve 21 and narrowed transversely as it approaches the bore thereof, so that at the bore each passage forms a rectangular port adapted to register with ports 25 and 26 formed respectively at the bottom and at one side of the tubular arm 14, as shown clearly in Fig. 3. In that portion

of the sleeve which fits around the collar 20 there is a radial opening in which is slidably fitted a shouldered pin 27, the head of said pin being slidable within a cap 28 screwed into a boss on the sleeve, as shown in Figs. 2 and 4. Disposed within the cap 28 is a spring 29 which presses the pin inward toward the collar 20. The inner end of the pin is rounded and fits in a groove in the collar, said groove being of the circumferential extent shown in Fig. 4, and having in the bottom thereof three depressions or seats 35, 45 and 55, adapted to receive the end of the pin and to yieldingly retain the sleeve 21 in the respectively adjusted positions at which the pin is in register with said seats.

The rod or shaft 19, after passing through the slot 18 in the bearing-member 13, extends through and fits revolvably within a cylindrical boss 60 which is formed integrally with the hub-portion of the arm 14, said boss extending back from the hub in axial alignment with the tubular forwardly extending part of the arm. At its rear end the shaft 19 carries a cylindrical cam-body 61 which has a helical groove 62 in the outer portion thereof. A tubular sleeve 63 fits slidably over the cam-body 61 and boss 60, the rounded rearward end of said sleeve being filled to form a weight 64. In the lower side of the sleeve 63, near the front end thereof, a longitudinal slot 65 is formed therein, and a small pin 66, carried on the boss 60, extends into said slot as shown in Fig. 8, so as to prevent rotation of the sleeve but to permit free longitudinal movement thereof relative to the boss. A pin 67, carried on the inside of the sleeve, extends into the helical cam-groove 62, whereby rotation of the shaft and cam-body causes longitudinal movements of the sleeve, thus moving the counterweight formed by said sleeve and the weight 64, toward or from the axis of the bearing-member 13 according to the direction of rotation.

The several parts above described are so constructed and proportioned that when the sleeve 21 is in a position at which the pin 27 enters the seat 35, the diaphragm 31 is in a vertical position, or perpendicular to the face of the record-disk V on the table A, the sleeve 63 is at the extreme forward position shown in Figs. 1 and 2, and the passage 34 is in register with the port 26 of the tubular arm 14, while the openings to the passages 44 and 54 are opposite imperforate parts of said arm. This is the operative position for the diaphragm 31, which is adapted for use with sound-records of the type (a) first herein mentioned, wherein the undulations of the groove are lateral or in the plane of the disk. A stylus-lever 36 has one end secured to the center of the diaphragm 31, and extends diagonally downward and forward therefrom, being pivoted

- between lugs 37 on the ring 33, and the lower end of the lever having a socket for a removable stylus 38 which is retained therein by a set-screw 39. The stylus rests upon the 5 face of the record in an inclined or angular position, and the pressure of the stylus against the record is proportional to that part of the weight of the sound-box and the arm 14 which is not counterbalanced by the 10 weight of the parts 60, 61, 63 and 64, it being understood that the several parts are so proportioned as to result in a proper stylus-pressure for records of the type mentioned above.
- 15 To adapt the mechanism for use with records of the second type (b) hereinbefore mentioned, it is merely necessary to rotate the sleeve 21 about the tubular arm 14 from the position above described, in the 20 direction of the arrows in Figs. 3 and 4, until the yieldable stop-pin 27 enters the seat 45 in the collar 20. At this position the diaphragm 41 is parallel with the face of the record P on the table A, the passage 25 44 is in register with the port 25 in the lower side of the tubular arm 14, the passages 34 and 54 are opposite imperforate parts of the tubular arm, and the sleeve 63 with the counterweight 64 is moved slightly 30 backward, as shown in Figs. 5 and 6, so that the effective counterweighting of the sound-box is slightly greater than before. A stylus-lever 46, connected with the center of the diaphragm 41, is pivoted between lugs 35 47 on the ring 43, and has a downwardly and forwardly extending chuck or clamping socket 49 which retains removably a stylus 48. Said stylus has a rounded or ball-shaped point adapted to enter the U-shaped 40 grooves of the record P, and engages said record at an angular or inclined position, as indicated in Fig. 5.
- By rotation of the sleeve 21 about the arm 14 until the stop-pin 27 enters the seat 55, 45 the mechanism is adjusted for use with records of the third type (c) hereinbefore mentioned. At said position of the sound-box the diaphragm 51 is parallel with the face of the record E on the table A, the passage 54 is in register with the port 25 of the arm 14, the passages 34 and 44 are opposite imperforate parts of the tubular arm, and the counterbalancing sleeve and weight 64 are at the extreme rearward position shown 50 in Figs. 7 and 8. A stylus-lever 56, secured to the center of the diaphragm 51, is pivoted between lugs 57 on the ring 53, and at its forward end has a vertical downwardly extending part 59 terminating in a relatively sharp or V-shaped stylus-point 58, preferably formed by a diamond or other extremely hard material suitable for permanent use, set in the end of the vertical part 59. The stylus of this character requires less 55 pressure upon the record than those of the two preceding types, and the reduced pressure is obtained by having the automatically variable counterweight 63-64 at the extreme rearward position, where it has the greatest tendency to counterbalance the 70 weight of the sound-box.
- Special attention is directed to the fact that the styli 38, 48 and 58 are so arranged that when in operative position the points thereof will each be the same distance from 75 the vertical pivotal axis of the tone-arm 11, so that, without change of length of the tone-arm, each stylus will traverse a record with the point moving along an arcuate line, such as the line "r" in Fig. 2, nearly 80 radial to the record-disk, and such that the line if continued will pass through the center of the disk. Each stylus and stylus-lever is also arranged so that when in operative position it will lie in a vertical plane 85 substantially tangent to the record-groove at the point of contact of the stylus therewith, and extending through the pivotal axis of the tone-arm. Thus, it will be seen from Fig. 2 that the stylus-lever 36 is offset laterally from the center of the arm 14 the same distance that said arm is offset laterally from the tone-arm 11; and from Figs. 6 and 7 it will be seen that the stylus-levers 46 and 56 are disposed angularly to the longitudinal axis of the arm 14 on which the sound-box is mounted, so that when in operative position the direction of the vertical plane in which said levers and their styli lie is such as to pass through the vertical 90 pivotal axis of the swinging tone-arm and be substantially tangent to the record-grooves at the point of contact of the styli therewith. The described positions of the several styli when in operation are desirable 95 in order that the same may "track" in the grooves of the record in the same way as the recording styli used in the production of the original or master records of which the commercial sound-records are duplicates; and unless the styli are arranged in this manner the same will be inclined laterally from the vertical plane tangent to the record-grooves at the point of contact, and the styli will "ride" one side or the other of 100 the grooves, resulting in imperfect reproduction of the recorded sounds, excessive and uneven wear of the records, and a tendency, particularly with the angularly disposed styli, for the reproducer to skid or 105 swing across the records transversely of the 110 grooves.
- A further refinement of structure is to be noted in the form of the stylus-levers near the ends thereof which are connected with 115 the diaphragms. Referring to Figs. 2, 5 and 8, it will be seen that the main portion of each stylus-lever extends substantially parallel with the diaphragm from the pivotal axis of the lever to a point slightly be- 120 130

yond the center of the diaphragm, then turns in perpendicularly to the diaphragm, and finally at the face of the diaphragm turns back toward the pivotal axis of the lever, the return-bent end-portion being attached to the diaphragm. The advantage of this structure may be perceived by reference to Figs. 9 and 10, in connection with the following: Unless a very small diaphragm or an excessively long stylus-lever is used, it is not practicable to pivot the stylus-lever in the plane of the diaphragm, this being an arrangement which would be desirable as resulting in movements of the attached end of the lever exactly perpendicular to the diaphragm. In avoiding excessive length of the stylus-lever with a large diaphragm (which it is desirable to use for the sake of tone-volume and fullness of the reproduced sounds), the pivot or fulcrum of the stylus-lever is offset from the plane of the diaphragm; but, as a result of said offsetting of the lever-fulcrum, the attached end of the lever tends to move angularly to the diaphragm, or in the direction of the line α tangent to the arc γ struck from the lever-fulcrum α in Fig. 9. With a rigid stylus lever, the tendency of said angular movement is to distort the diaphragm unsymmetrically, the greater bowing thereof occurring at the side opposite the lever-fulcrum, as indicated by dotted lines in Fig. 9, and the other side or half of the diaphragm being but slightly bowed, or even assuming a curvature opposite in direction to that of the principal curvature or bowing first mentioned. Obviously such unsymmetrical distortion of the diaphragm is undesirable and will result in imperfect sound-reproduction. With a lever extending in a substantially straight line from the pivotal axis thereof to the diaphragm, as in Fig. 9, if the lever be made sufficiently flexible to compensate for the angular variation and thus permit the attached end to move exactly perpendicularly to the diaphragm, there will be a marked loss of volume of the reproduced sounds, due to the cushioning or absorbing of the vibration in the flexible lever. Referring now to Fig. 10, it will be seen that the main portion of the stylus-lever may be sufficiently rigid to give full tone-volume in the reproduction, and that a slight lateral flexibility of the inwardly turned end-portion of the lever will fully compensate for the tendency to move angularly at the face of the diaphragm, enabling the attached end of the lever to move exactly perpendicularly to said face, whereby to produce a symmetrical distortion or bowing of the diaphragm. As the sound-vibrations are transmitted longitudinally of the inturned end-portion of the lever, it will be obvious that the necessary lateral flexibility thereof may be attained without reducing the capacity of the

lever to transmit fully the vibrations received from the stylus, to thus produce the maximum tone-volume. The extent of the diaphragm-distortion indicated in Figs. 9 and 10, is, of course, greatly exaggerated in 70 order to clearly illustrate the described tendencies of the different structures, and their resultant effects upon the quality of tone-reproduction.

Referring again to the adjusting operations of the mechanism necessary in changing from one type of record to another, it will be noted that all necessary adjustment of the mechanism is effected by merely turning the multiple sound-box about the arm 75 14 so as to place the proper stylus in the operative or playing position therefor. The extent of the slot 18 in the bearing-member 13 is such as to permit lifting of the sound-box to a height sufficient to entirely clear the 80 face of the table A or a record-disk thereon, when rotating the sound-box to the desired position. It will be apparent that, by the simplicity of adjustment, the use of separate styli and stylus-levers for each type 85 90 of record, and the perfect adaptation of each unit to its particular type, records of all the standard and commercially known styles may be used without special knowledge or skill on the part of the user, and all values 95 of the several types of record preserved as fully as when the same are used in connection with machines for the single types only.

Now, having described my invention, what I claim and desire to secure by Letters Pat- 100 ent is:

1. Sound reproducing mechanism including a tubular arm mounted to swing vertically and horizontally; a sound-box mounted rotatably upon a portion of said arm and having a plurality of diaphragms and styli adapted to be brought into operative position serially by rotating said sound-box to predetermined positions upon the arm; means for counterbalancing a portion of the 11 weight of the sound-box and arm, and means actuated by rotation of the sound-box for automatically varying the effective counterbalance according to the position of the sound-box upon the arm. 11

2. Sound reproducing mechanism including a tubular arm mounted to swing about a fixed axis, a sound-box mounted rotatably upon a portion of said arm and having a plurality of diaphragm-chambers formed 12 therein, there being ports in the tubular arm adapted to register with passages through the sound-box extending to the respective diaphragm-chambers, diaphragms mounted for vibration in said chambers, stylus-levers 13 connected with said diaphragms and extending diagonally to the longitudinal axis of the tubular arm, and styli carried by the several stylus-levers and movable into operative position solely by rotation of the sound-box 14

- about the arm, the points of said styli when in operative position being substantially equidistant from the fixed axis of the tubular arm.
5. Sound reproducing mechanism including a horizontally swingable tone-arm, a tubular arm connected with said tone-arm and swingable vertically, a sound-box mounted rotatably upon said tubular-arm
10. said sound-box having a plurality of diaphragm-chambers therein with passages extending therefrom and adapted to register with ports in the tubular arm, diaphragms mounted in said chambers, a stylus-lever for each diaphragm, said stylus levers being pivoted upon the sound-box and operatively connected with the respective diaphragms, the pivots of the several stylus-levers being in fixed and invariable radial relation to the axis of the tubular arm about which the sound-box is rotatable, and said stylus-levers being adapted for holding styli in operative record-engaging position when the sound-box is rotated to the positions at which the 25 passages from the respective diaphragm chambers are in register with the ports in the tubular arm.
4. In a mechanism of the class described, a tone-arm pivoted upon a fixed vertical axis, a normally horizontal tubular arm jointed to said tone-arm and swingable vertically, a sound-box having a central bore and a plurality of diaphragm-chambers arranged symmetrically thereabout and having passages communicating with said bore, diaphragms mounted in said chambers, a stylus-lever and stylus for each diaphragm, the tubular arm fitting within the central bore of the sound-box so that the latter is rotatable thereon, said arm having a port adapted to register with the passage from one diaphragm-chamber when the respective diaphragm is vertical and the stylus-lever and stylus thereof in operative relation to a horizontal record-disk, said arm having a second port adapted to register with the passages from the other diaphragm-chambers when the respective diaphragms are horizontal and their stylus-levers and styli are in operative relation to a horizontal record-disk, the points of the several styli when in operative position being substantially equidistant from the pivotal axis of the tone-arm, the several styli and stylus-levers when in operative position lying sub-

stantially in vertical planes intersecting the pivotal axis of the tone-arm, and the several styli being movable to operative position solely by rotation of the sound-box about the tubular arm.

5. In a mechanism of the class described, a multiple sound-box having a plurality of diaphragms and styli operatively connected with the respective diaphragms, a member carrying said sound-box and mounted to swing in a vertical plane, the sound-box being rotatable on said member to a series of positions at which the several stylus-and-diaphragm units are successively in operative position, means for counterbalancing a part of the weight of the sound-box, and means actuated by rotation of the sound-box for varying the effective counterbalance.

6. In a mechanism of the class described, a multiple sound-box having a plurality of diaphragms and styli connected operatively with the respective diaphragms, a vertically swingable arm carrying said sound-box, the sound-box being rotatable about said arm and the several stylus-and-diaphragm units being moved into operative positions solely by rotation of the soundbox about the arm, a movable counterweight for the sound-box, and actuating means connecting the sound-box and said counterweight, whereby the latter is moved to a definite position for each position of the sound-box relative to the arm.

7. In a mechanism of the class described, a horizontally swingable tone-arm having a laterally turned hollow bearing-portion, a tubular arm mounted on said bearing-portion and swingable thereabout in a vertical plane, a multiple sound-box having a plurality of diaphragms and styli operatively connected with the respective diaphragms, said sound-box being mounted rotatably upon said tubular arm and movable about said arm to bring the several stylus-and-diaphragm units successively into operative positions, a movable counterweight for the sound-box, and an actuating member for said counterweight, said actuating member being inclosed by the tubular arm and rotatable therein and connected fixedly with the sound-box whereby relative rotative movement of the sound-box and said arm may definitely vary the position of the counterweight.

E. J. RODGERS.
